UNITED STATES PATENT OFFICE.

WILLIAM W. GRIGSBY, OF LAWHON, LOUISIANA.

LISTENING APPARATUS FOR TELEPHONES.

No. 841,244.

Specification of Letters Patent.

Patented Jan. 15, 1907.

Application filed June 12, 1906. Serial No. 321,396.

To all whom it may concern:

Be it known that I, WILLIAM W. GRIGSBY, a citizen of the United States, residing at Lawhon, in the parish of Bienville and State 5 of Louisiana, have invented a new and useful Listening Apparatus for Telephones, of which the following is a specification.

The principal object of the present invention is to provide an apparatus whereby the 10 superintendent or chief operator of a telephone-exchange may overhear conversations carried on between the switchboard operator and the different subscribers.

A further object of the invention is to construct an apparatus of this type by which 15 the connections may be made without the knowledge of the switchboard operator.

With these and other objects in view, as will more fully hereinafter appear, the invention 20 consists in certain novel features of construction and arrangement of parts hereinafter fully described, illustrated in the accompanying drawings, and particularly pointed out in the appended claims, it being 25 understood that various changes in the form, proportions, size, and minor details of the structure may be made without departing from the spirit or sacrificing any of the advantages of the invention.

In the accompanying drawings, Figure 1 30 is a general diagram of a listening apparatus arranged and constructed in accordance with the invention. Fig. 2 is a plan view of the mechanism employed by the chief operator for determining the telephone-line with 35 which he is in communication. Fig. 3 is an inverted plan view of the same. Fig. 4 is a transverse sectional view of the mechanism on the line 4 4 of Fig. 2. Fig. 5 is a plan 40 view of the circuit-closing devices employed adjacent to the telephone switchboard for connecting to the various lines. Fig. 6 is an inverted plan view of the same. Fig. 7 is a cross-section of the mechanism on the line 45 7 7 of Fig. 5.

Similar characters of reference are employed to indicate corresponding parts throughout the several figures of the drawings.

In carrying out the invention an apparatus (designated generally A in Fig. 1) is placed at some point adjacent to the switchboard, and the apparatus B may be placed at any desired distance therefrom, preferably 50 in the office of the chief operator, and the

latter by listening at a telephone C may overhear the conversation on any line with which he chooses to be placed in communication.

The mechanism which is placed adjacent to the switchboard comprises a suitable base- 60 plate 10, through which extends a vertically-disposed shaft 11, having upper and lower bearings 12, that are carried by suitable brackets or bridge members 15. This shaft carries an arm 16, that is formed of insulating 65 material, and is provided with two contacts 17 and 18, preferably in the nature of spring-brushes. The shaft carries or is formed of separate metallic sleeves 19 and 20, that are insulated from each other, and these are engaged, respectively, by brushes 21 and 22. The sleeves are electrically connected to the traveling contacts 17 and 18, and thus are in electrical connection with the brushes 21 and 22, respectively. These brushes are carried 75 by studs or binding-posts 24 and 25, from which lead current-conducting wires 26 and 27.

Secured to the shaft is a crown-ratchet 30, the teeth of which are arranged to be engaged by a pawl 31, carried by an armature 32, that is disposed within the field of force of an electromagnet 33, and said electromagnet is connected in a circuit which includes the wire 27 and a wire 34. Each time the 80 electromagnet is energized the ratchet is advanced to the extent of a single tooth and the shaft is rotated and arm 16 is carried around one step. When the ratchet-wheel is advanced, it is locked and held in the ad- 85 justed position by a suitable pawl 35.

Arranged on the base 10 are two sets of contacts 36 and 37, these being arranged each in circular series concentric with each other and with the axis of the shaft 11. The 90 contacts are in radially-arranged pairs that are connected in circuit by the contacts 17 and 18. Leading from each pair of contacts are wires 40 and 41, that are connected to the opposite ends of the secondary of an inducto- 95 rum 42, the primary 43 of the inductorium being in series with one of the line-wires. In the diagram five line-wires *a b c d e* are shown, and each includes the primary of the induction-coil, and adjacent to each primary is a 100 secondary coil that is connected to two of the contacts 36.

It is obvious that if a circuit be closed through the electromagnet the latter will be 105 energized and the pawl 31 will advance the 110

ratchet 30 to the extent of a single tooth, so that the contacts 17 and 18 will be moved from engagement with one pair of contacts 36 into engagement with another pair of contacts 36, and as each set or pair of contacts 36 is inductively related to a different line any one of the lines may be placed in communication with the circuit of which the wires 26 and 34 form a part.

15 At the office of the chief operator or other person whose duty it may be to listen to a conversation is placed an ordinary telephonic apparatus, which is indicated at C, and the indicating apparatus B, the construction of the latter being best shown in Figs. 2, 3, and 4. The indicating apparatus includes a base-plate 45, having an opening for the passage of a shaft 46, that is mounted in bearings 47, carried by bridges or brackets 48, secured to the base. Secured to the shaft is a crown-ratchet 50, which is engaged by a pawl 51, carried by an armature-lever 52, that is disposed within the field of force of an electromagnet 53, and each time the electromagnet 25 is energized the crown-ratchet will be advanced to the extent of a single tooth. The ratchet is held from movement in the reverse direction by a lock-pawl 54. To the upper portion of the shaft is secured a revolute pointer 55, that is arranged to move over a circular dial 56, bearing numerals of a number corresponding to the number of pairs of contacts 36 carried by the member A, and the electromagnets 33 and 53 are connected in series, so that a circuit closed through one will be closed through both, and they will be simultaneously operated. The chief operator can, therefore, instantly determine the line with which the contacts 17 and 18 are in 35 communication.

40 Tracing now the circuit from the electromagnet 33, it will be seen that wire 26 is connected to the electromagnet 53, and this through wire 57 to the primary 58 of an induction-coil, thence leading to a battery 59, a circuit-closer 60, and from the latter through the wire 61 to the electromagnet 33.

45 The switch or key 60 may be in the form of a telegraph-key and may be depressed by the chief operator for the purpose of closing an energized circuit through the electromagnets 33 and 53. This will result in advancing the contacts 17 and 18 into engagement with the successive pairs of contacts 36, and the secondaries 43 of the different lines will therefore be successively connected with the telephone C of the chief operator, who by listening may determine the manner in which the switchboard operator is attending to business.

50 I claim—

1. In listening apparatus for telephone exchanges, a movable-contact carrier, contacts arranged to be successively engaged thereby and connected in circuits that are inductively

related to the telephone-line, means for imparting a step-by-step movement to the movable-contact carrier, and a telephone-receiver electrically connected to the movable contacts.

2. In listening apparatus for telephone systems, an annular series of stationary contacts connected in circuits that are inductively related to the telephone-line, a revolute contact-carrying arm, movable contacts 75 arranged on the arm and adapted to engage the stationary contacts, a telephone-receiver connected to the movable contacts, and means for operating the revolute contact-carrier.

3. In listening apparatus for telephone systems, an annular series of stationary contacts arranged in circuits that are inductively related to the stationary lines, a revolute contact-carrying arm, means for revolving 85 the same, contacts supported by said arm and arranged to engage the successive stationary contacts, and a telephone-receiver arranged in a circuit of which the movable contacts form the terminals.

4. In listening apparatus for telephone systems, an annular series of stationary contacts, said contacts being arranged in circuits that are in communication with the different telephone-lines, a shaft, collecting rings or 95 sleeves on said shaft, brushes engaging said rings or sleeves, a stationary receiver connected in a circuit that extends between said brushes, an arm carried by the shaft, contacts supported by said arm and arranged to 100 engage the stationary contacts, a ratchet on the shaft, and an electromagnetically-actuated pawl for imparting a step-by-step movement to said ratchet.

5. In listening apparatus for telephone 105 systems, a base-plate, contacts carried by the base-plate and arranged in continuous annular series, all of said contacts being insulated from each other, current-conductors leading from the contacts and in communication 110 with the different telephone-lines, a shaft arranged at the center of the series of contacts, an arm carried by said shaft, movable contacts carried by the arm and arranged to engage the stationary contacts, collecting- 115 sleeves on the shaft, said sleeves being connected to the movable contacts, brushes engaging said sleeves, a telephone-receiver in a circuit of which the sleeves form terminals, a ratchet secured to the shaft, a pawl engaging 120 said ratchet, an electromagnet for actuating the pawl, said magnet being arranged in the circuit of the receiver.

6. In listening apparatus for telephone-receivers, a pair of spaced base-plates, an annular series of contacts carried by one of said base-plates, and inductively related to the different telephone-lines, movable contacts arranged to engage the stationary contacts, a 125 step-by-step ratchet mechanism for advanc- 130

ing the movable contacts and including an electromagnet, an indicating - dial on the other base-plate, a shaft at the center of the dial, a pointer on said shaft, a step-by-step mechanism for turning the shaft, said mechanism including an electromagnet, a circuit extending from the movable contacts through both of the electromagnets, said circuit including also a key or switch, a source of electrical energy and the primary of an inducto- rium, and a telephone-receiver connected to the secondary of the inductorium.

In testimony that I claim the foregoing as my own I have hereto affixed my signature in the presence of two witnesses.

WILLIAM W. GRIGSBY.
